DESIGN FOR A SUIT

Virginia Gray, St. Louis, Mo.

Application February 19, 1941, Serial No. 99,107

Term of patent 3½ years

To all whom it may concern:

Be it known that I, Virginia Gray, a citizen of the United States of America, residing in St. Louis, and State of Missouri, have invented a new, original, and ornamental Design for a Suit, of which the following is a specification, reference being had to the accompanying drawing, forming part thereof.

Fig. 1 is a front view of a suit showing my new design.

Fig. 2 is a rear view thereof.

I claim:

The ornamental design for a suit, as shown.

VIRGINIA GRAY.
